MEANS FOR CLEANING DISPENSING SYSTEMS

Sabatino Petricone, Cincinnati, Ohio

Application April 9, 1935, Serial No. 15,439

5 Claims. (Cl. 225—12)

My invention relates to means for cleaning the piping, coils and tubing used in connection with dispensing systems for dispensing beer and other beverages.

It is well known that the inner faces of pipes and their coils which convey beer in dispensing systems become coated and slimy, thereby deleteriously affecting the beer and causing clogging of the pipes and their coils. Hence it is customary to periodically clean the insides of the pipes and coils of dispensing systems.

This cleaning is usually accomplished by flushing the pipes and coils with steam. This method is cumbersome and expensive, because a device for generating and injecting steam under pressure is necessarily complicated, and it also entails the use of heat with its accompanying danger of fire, and its conveyance. It also results in baking deleterious foreign matter in the coating and slime upon said inner faces, and in failure to properly hygienically clean said faces.

It is the object of my invention to avoid these objections, and to provide means whereby the insides of the pipes and coils are cleaned by novel successive treatments.

My invention consists in novel means for flushing the pipes of a dispensing system with water, introducing compressed air into the water, for agitating the same and increasing its flow, introducing a cleaning agent, preferably having an alkaline base, dissolved in water, into the pipes and circulating the same therein, introducing compressed air into such cleaning solution, removing the cleaning solution, and again flushing the pipes with water; and, further, in novel means for subjecting the pipes of a dispensing system to successive novel treatments in novel manner to clean the same.

My invention consists further in providing novel arrangements for connecting the piping for circulation of cleaning liquid therein; further, in providing novel means for controlling the direction of flow of cleaning liquid; further, in providing novel means for creating and controlling the introduction of compressed air into the cleaning liquid; further, in providing novel means for introducing a cleaning compound; further, in providing novel means for circulating the same; and, further, in providing a novel arrangement of means for introducing and controlling successive cleaning agencies in the dispensing system wherewith to clean said system.

The invention will be further readily understood from the following description and claims, and from the drawings, in which latter:

Fig. 1 is an elevational perspective view of an ordinary dispensing system for beer shown in connection with my improved cleaning means and arranged to be cleaned by my improved method, partly in section and partly broken away.

Fig. 2 is a longitudinal sectional view of the pump and controlling means used in connection with my improved cleaning means, taken in the plane of the line 2—2 of Fig. 3, and partly broken away.

Fig. 3 is a longitudinal sectional view of the same, taken on the line 3—3 of Fig. 1, and partly broken away.

Fig. 4 is a cross-sectional view of a detail of the same, taken in the plane of the irregular line 15 4—4 of Fig. 2, and partly broken away.

Fig. 5 is a cross-sectional view of a further detail of the same, taken in the plane of the line 5—5 of Fig. 2, and partly broken away.

Fig. 6 is a cross-sectional view of a detail, taken in the plane of the line 6—6 of Fig. 2.

Fig. 7 is a cross-sectional view of the coupling means for the pipes taken in the plane of the line 7—7 of Fig. 1; and,

Fig. 8 is a longitudinal sectional view of the coupling between one of the hoses and one of the beer faucets, taken on the line 8—8 of Fig. 1.

In the present invention it is intended to use a flow of liquid fed through the pipes and their coils to be cleaned, with sufficient velocity to remove the larger amount of obstructing foreign matter clinging to the insides of the pipes. The remaining foreign matter is then completely removed and the pipes thoroughly cleansed by introducing a cleaning agent into the pipes and circulating the same through all of the pipes.

Rinsing fluids are then fed through the pipes for expelling the cleaning agent and rinsing the pipes preparatory to their re-use.

To clearly show the application of my improved cleaning method, there is exemplified in Fig. 1 an ordinary dispensing system for beer.

A bar or stand 11 is shown provided with a number of beer faucets 12. Although three of the same are shown in the present exemplification, it is understood that one or any number of the same may be present, and my improved device is applicable to a system comprising any number of faucets.

The bar 11 is also provided with a shelf 13 on which glasses and similar receptacles are supported preparatory to and while being filled from the faucets, and having a drain box 14 thereunder. The bar is shown as extending to the floor 15 beneath which are the kegs or similar con-

ainers 16 of beer. The kegs are usually positioned on the floor of the room beneath the one containing the bar, which room is usually the basement or cellar.

5 There are pipes 17 connecting the faucets 12 with the kegs and provided at their lower ends with flexible connecting portions 18 having coupling members 19 for connecting the same to the kegs. Threaded extensions 20 on attachments 21 10 on the kegs are shown to which the coupling members 19 are fitted. Each of the attachments comprises a tube 22 with which the flexible portion of the pipe communicates and which extends to substantially the bottom of the keg.

15 A pipe 23 connected to a suitable source of gas under pressure, such as a tank of compressed carbon dioxide gas or air, is provided with a shut-off valve 24 and with flexible branch tubes 25 arranged to be connected to the attachments 21 20 on the kegs and communicating with the top of the inside of the kegs for applying pressure on top of the beer in the kegs and causing the same to flow upwardly through the pipes 17 to the faucets.

25 Near the faucets, the pipes 17 are provided with coils 26 forming continuations of the pipes and located in an inclosure or box 27 in the interior of the bar. Ice may be packed in the inclosure or box about the coils for cooling the beer. A usual water faucet 28 is provided on or near the bar to supply rinsing water for the glasses.

The cleaning means comprises a pump 29 having a pump chamber 30 in a hollow cylinder 31, securely fastened at its lower end to prevent leakage, as by welding, in a recess 32, in a base 33, and provided at its upper end with a cap 34, removably secured to the cylinder in manner to prevent leakage. The base is provided with foot flanges 35 on which the operator stands when using the pump. A piston 36 is arranged for reciprocating movement within the compression chamber and is secured to the lower end of a rod 37. The upper end of the rod is provided with a handle 38 threaded thereto.

40 The piston 36 comprises a disk 39 threaded over the reduced threaded end 40 of the piston rod against a shoulder 41 on the rod. The lower face of the disk forms a seat 42 for a valve 43. A valve guide 44 is screwed over the threaded end 40 of the piston rod against the disk 39, and is provided with radial wings 45 between which grooves 46 are located, the grooves extending throughout the height of the guide.

45 The lower ends of the wings have radially extending flanges 47 forming stops for the lower end of the valve 43.

50 The valve 43 comprises a sleeve 48 which is shorter than the space between the disk 39 and the flanges 47 and reciprocates on the outer edges of the wings 45. Its upper end is provided with an annular valve-rib 49 which coats with the valve seat 42 for closing passage through the grooves 46, the lower ends of which are continuously open to the space in the cylinder 31 under the piston 36. When the piston is moved downwardly the valve 43 is closed, and when the piston is moved upwardly the valve is open.

55 The outer periphery of the sleeve is threaded as shown at 50, its upper end being provided with an annular flange 51 below the valve-rib 49. A cup washer 52 has an inwardly extending flange 53. A collar 54 is threaded over the threaded portion 75 of the sleeve. The flange 53 of the cup washer

is clamped between the flange 51 and the collar 54.

The cup washer is of flexible material, for instance, leather. There is an annular space 55 between the skirt of the cup washer and the lower end of the sleeve. When the piston is moved downwardly the cup washer is spread by the pressure thereunder for frictional engagement with the inner wall of the cylinder for pushing the fluid thereunder out of the lower end 10 of the cylinder and creating suction above the piston. When the piston is moved upwardly the skirt of the cup washer collapses for forming a passage between it and the wall of the cylinder.

The recess 32 in the bottom wall of the compression chamber connects with a passage 56 in the base. This passage terminates in another recess 57 in the base. A tube 58 is securely held to the wall of the recess 57 and extends upwardly in substantial parallelism with the cylinder 31. 20

25 The cap 34 is provided with a hole 59, the wall of which is threaded at its outer end as at 60, and has an inwardly laterally extending annular flange 61 at its inner end. A packing 62 and an adjusting gland nut 63 are received in the hole, 25 the gland nut compressing the packing between it and said flange against the piston rod and forming a fluid tight joint for the piston rod.

30 Formed integrally with the cap 34 and supported thereby is a valve casing 65 provided with a tapered bore 66. Arranged for rotative movement in the tapered bore is a tapered valve plug 67 provided with interior passages 68 and 69, having an interior separating wall 70 between them. A series of openings 73 and an opening 74 in the side walls of the valve plug 67 communicate with the passage 69, and an opening 75 diametrically opposite to the opening 74 communicates with the passage 68. The lower end of the passage 68 opens into a space 76 in 40 the valve casing beneath the valve plug, and the lower end of the interior separating wall connects with the outer wall of the plug.

35 There is a passage 77 between the tapered bore 66 and the upper part of the pump chamber. 45 Selective openings 73 register with the passage 77, so that communication between the passage 69 and the top of the pump chamber is had throughout all positions of the valve plug.

40 The valve casing 65 has two ports 78 and 79, 50 diametrically opposite each other and an intake port 80 midway between the two. On the sides of the valve casing there are extensions 81, 82 having passages 83, 84 therein communicating with the ports 78 and 79. An externally 55 threaded boss 85 is provided at the side of the valve casing midway between the extensions 81, 82 and has a passage 86 therein communicating with the port 80. The internally threaded end of an L 87 is received over the threaded boss 60 85 and the other end of the same is of a reduced cross-section, as shown at 88.

45 The upper end of the tube 58 is securely held in a bore 91 in an extension 92 of the valve casing, and the bore forms a passage communicating 65 with the passage in the tube 58 and the interior of the valve casing. A check valve 93 in the passage 91 is shown as a ball in the space 76 beneath the valve plug. It is held by gravity against an annular seat 94 at the mouth of the 70 passage 91 to prevent downward flow of fluid in the passage 91 while permitting fluid under pressure in the passage to unseat the ball and flow into the space 76.

50 The valve plug 67 is provided at the top thereof 75

with a stem 95 to which a handle 96 is fixedly secured, as by having a square opening 97 received over a correspondingly shaped end of the stem. The head of a screw 98 threaded into the 5 end of the stem clamps a washer 99 against the handle for holding it to the shaft. A gland nut 101 is received about the stem 95 and is threaded into the end of the tapered bore 66. A packing washer 102 is forced against the top of the valve 10 plug and the sides of the tapered bore by the gland nut 101 for sealing said bore against the 10 escape of fluid.

One end of a hose 105 is received and clamped over the extension 81 and the end of a similar 15 hose 106 is received and clamped over the extension 82. The other ends of the hoses 105 and 106 are provided with connecting attachments 107 and 108 respectively. The connecting attachments are arranged to be securely but removably fitted to the beer faucets 12 whereby fluid 20 under pressure may be forced through the hoses and through said faucets to avoid leakage and withstand pressure.

One end of a third hose 109 is received and clamped over the reduced end 88 of the L 87. The other end of this hose is provided with a 25 connecting attachment 110 similar to the attachments 107 and 108 and arranged to be similarly securely but removably fitted to the water 30 faucet 28 for feeding water under pressure to the intake port 80.

The attachments 107, 108 and 110 are of usual construction and are of the type used in connecting hoses to faucets when the ends of the 35 faucets are not provided with threads. The insides of these attachments are provided with resilient walls 111 which resiliently hold to the faucets. Straps 112 about the faucets and connected to the attachments may aid in holding the 40 attachments in place.

In Fig. 1 the lower ends of the pipes are shown disconnected from the kegs and interconnected, as by having the coupling members 19 thereof fitted, as by a threaded connection 113 to a cross 45 coupling 114. Said cross coupling is shown as having branches 115 provided with passages 116 which communicate with each other. The pipes 17 are respectively connected with three of these branches, the fourth being closed by a cap 117.

When the pipes 17 and their coils 26 are to be cleaned, the coupling members 19 are disconnected from the attachments 21 on the kegs and connected to respective branches of the cross 50 coupling 114, for providing communication between all of the pipes and coils. The attachment 110 on the end of the hose 109 connecting with the intake port 80 of the valve casing is then fitted on the water faucet 28. The faucet 28 is then 55 opened, the valve plug being in neutral or closed position as shown in Figs. 2, 3, 4 and 5, the corresponding position of the handle being represented by the dotted outline of the same shown at *a* in Fig. 4. No flow of water takes place because the passage 68 communicates only with the space 66, which space is sealed against the escape of the water by the check valve 93 in the passage 91.

One of the hoses 105, 106, is connected to one 60 of the beer faucets, and this faucet and another beer faucet are opened. The valve plug is now 65 turned through an angle of forty-five degrees toward that side of the valve casing 65 from which the hose attached to the beer faucet extends. If the hose 105 is connected to the beer faucet, the valve plug is turned through an angle 70 of forty-five degrees to a position as represented

by the dotted outline of its handle shown at *b* in Fig. 4. When the plug is in this position the opening 75 in the wall of the valve plug is in communication with the ports 80, 78, and water from the faucet 28 flows through the hose 109, 5 the port 80, the opening 75 and passage 68, the port 78, hose 105, and through the beer faucet. Thereafter the water flows through the coil and its depending pipe, through the cross coupling 114 and up another of the pipes and its coil and 10 out through the other open beer faucet. This flow discharges the more readily soluble portions of the coating and slime in the pipes. The pump 29 is then operated and air is forced through the passage 91 past the check valve 93 into the space 15 16 and through the passage 68, where it meets the stream of water and joins with it for increasing the velocity and pressure of the same, agitating the cleaning water, and releasing and discharging additional coating and slime. 20

When the valve plug is in the position just described the opening 74 in the wall of the valve plug communicates with the port 79 in the valve casing, and several of the openings 73 are in registry with the passage 71. Thus air is drawn 25 in through the hose 106 and feeds through the valve plug into the pump cylinder above the piston. On the upward stroke of the piston the air passes into the compression chamber for being compressed on the next downward stroke of the 30 piston.

When the stream of air and water has flowed through the two faucets and tubes for a time sufficient to dislodge and carry out of the tubes the larger particles of foreign matter, the beer 35 faucet through which the stream is issuing is closed and the other one is opened. The stream then moves through the pipe and coil connected with this faucet due to the cross coupling, and both initial rinsing and pressure rinsing are re- 40 peated.

This may complete the preliminary cleaning operation or the hose 105 may be connected to others of the beer faucets in turn for reversing the flow through them for effecting further preliminary cleaning. 45

The hose 105 has been described as the one leading to the beer faucet and 106 as the hose acting as the air intake for the pump, but it is obvious that if the hose 106 be connected to the 50 beer faucet and the valve plug turned through forty-five degrees from off position to the side at which the hose 106 is connected to the valve casing, the same operation will result. The handle of the valve plug is represented in this position 55 by the dotted outline *c* in Fig. 4.

After the pipes have been thus flushed, the same may be emptied by closing the faucet 28 for stopping the supply of water, and by operating the pump, whereupon the air forced through the 60 pipes clears them of water.

After the initial flushing it is desirable to further clean the pipes and their coils by circulating a cleaning agent dissolved in water through the tubes. 65

The cleaning agent I prefer to employ is a mixture having an alkaline base dissolved in water and having a solvent action on the coating and slime arising from the beer on the insides of the pipes and their coils, or the coating and slime 70 arising from other beverages.

For cleaning the pipes the valve plug is turned through an angle of 90 degrees from closed position. If the valve plug is turned in one direction the handle for the same will occupy the position 75

represented by the dotted outline *d* and if turned in the opposite direction will occupy the position shown by the dotted outline *e* in Fig. 4.

With the valve plug turned to a position ninety degrees from closed position, the opening 75 in the wall of the valve plug is in registry with either of the ports 78, 79, depending on the direction in which the valve plug has been turned, and the port 80 is closed by the side of the valve plug for shutting off the flow of water from the faucet 28.

That one of the hoses 105 or 106 which is connected to the side of the casing toward which the valve plug is thus turned is now connected to 15 one of the beer faucets and this faucet as well as another of the beer faucets is opened, and the end of the other of these hoses is submerged in a body of liquid containing the cleaning agent, this body being of sufficient volume to substantially fill the pipes being momentarily treated.

The other of the beer faucets is opened to prevent resistance to the incoming flow of the cleaning liquid or solution.

For the purpose of illustration let it be supposed that the hose 105 is connected to the third beer faucet from the left and the valve is turned to the position *d* as shown in Fig. 4. Then the outer end of the hose 106 is submerged in the cleaning liquid or solution and the pump operated.

Thereupon the liquid is upon downward stroke of the piston drawn by suction through the hose 106, the port 79, the passage 69 and the passage 77 and enters the top of the pump chamber. Upon upward stroke of the piston the liquid bypasses the same and enters the compression chamber, from whence it is fed, upon downward stroke of the piston, through the passages 56, 91 past the check valve 93 and through the passage 68, the port 78 and through the hose 105 past the beer faucet and into the pipe and its coil.

After several strokes of the piston the pipes and their coils being momentarily treated contain a substantial quantity of the cleaning liquid and the end of the hose 106 is removed from the body of liquid and fastened to one of the others of the beer faucets, shown as the second one of the same in the present exemplification.

With the hoses 106 and 105 connected to the second and third beer faucets respectively, the other beer faucet is closed and the pump operated for circulating the liquid. The action is the same as when the liquid was fed into the pipes, except that the circuit is now closed, and therefore the liquid after passing down through one pipe and its coil and up through the other, feeds back into the upper part of the pump chamber.

This circulating of the liquid continues for a time sufficient to completely remove all foreign matter from the insides of the tubes and coils connected with the second and third beer faucets, whereupon the hose 106 or the hose 105 is removed from the second or third beer faucet respectively and fitted to the first. The first faucet is then opened and the faucet from which the hose was removed is closed. The pump is then operated for again circulating the liquid until the first pipe and its coil is completely cleaned.

Upon the completion of cleaning of all of the pipes and their coils, one of the hoses 105, 106 is removed from its respective beer faucet, and the valve is turned to the position *b* or the position *c* and, as in the preliminary cleaning operation, the water from the faucet 28 circulates through the passage 68 in the valve plug and through the

beer faucet and the pipes and their coils for thoroughly rinsing the same. The velocity of the stream of rinsing water may be increased and the rinsing water agitated by the air forced into the same by operation of the pump, also as in the preliminary cleaning operation, thereby aiding in the rinsing operation.

Upon completion of each of the cleaning and rinsing operations, the pump may be operated for injecting a stream of air into the pipes and their coils and thereby forcing out any of the cleaning agents or water remaining in the pipes and their coils.

After the pipes and their coils have been rinsed the faucet 28 is closed, the hoses are removed 15 from the beer faucets and the lower ends of the pipes are removed from the cross coupling 114 and reconnected to the attachments 21 on the kegs, whereupon the system is ready for use in again dispensing beer.

Beer has been exemplified as the beverage dispensed. My invention is not limited to the kind of beverage dispensed, as it is applicable to any dispensing system regardless of the number of dispensing faucets or the beverage being dispensed.

My invention is simple and inexpensive, it enables the small dispenser to maintain clean pipes and coils, it is employable under conditions and in localities where steam cleaning is not available, it permits more frequent cleaning of the dispensing system, and makes the cleaning readily available by simple equipment.

I claim:

1. In means for cleaning the piping including a coil of a dispensing system, the combination of a pump having an inlet port and an outlet port, a valve casing between said ports comprising a port for a water supply, an inwardly closing check valve for said outlet port, a rotatable valve member in said casing between said inlet port, said water supply port and said check valve, said valve casing having a piping port communicating with said piping, said valve member having a pair of separated passages and a passage port for each 45 of said passages, a wall of said valve casing normally closing one of said passage ports, the other of said passage ports arranged to register with said water supply port and one of said piping ports, and said check valve having communication with said other of said passage ports.

2. In means for cleaning the piping including the coil of a dispensing system, the combination of a pump comprising a reciprocating pumping member and a port at each end of said pumping member, a valve between said ports, comprising a body and a movable valve member, an outwardly opening check valve between said movable valve member and one of said first-named ports, said movable valve member having a pair 60 of passages separated by a wall, each of said passages having a passage port, one of said passages having an additional port substantially continuously communicating with the other of said first-named ports, said valve body having a 65 water supply port, said valve body provided with a piping port for said piping, one of said passage ports of said movable valve member normally closed by a wall of said body and registerable with said piping port, and the other of said passage ports of said movable valve member selectively registerable with said water supply port, combinedly with said water supply port and said piping port, and with said piping port.

3. In means for cleaning the piping including

the coil of a dispensing system, the combination of a pump comprising a reciprocating pumping member and a pump port at each end of said pumping member, a valve between said pump ports comprising a body and a movable valve member, an outwardly opening check valve between said movable valve member and one of said pump ports, said movable valve member having a pair of passages separated by a wall, each 5 of said passages having a passage port, one of said passages further having a series of ports selectively communicating with the other of said pump ports, said valve body having a water supply port, said valve body provided with a piping port communicating with said piping, one of said passage ports normally closed by a wall of said body and selectively registerable with said piping port, and the other of said passage ports registerable selectively solely with said water 10 supply port, combinedly with said water supply port and said piping port and solely with said piping port, in which last-named relation one of said series of ports registers with said other of said pump ports.

25 4. In means for cleaning the piping of a dispensing system, the combination of a pump comprising a reciprocating member, a pump port at each end of said reciprocating member, a valve between said pump ports comprising a body having valve ports communicating with said respective pump ports and a valve plug between said valve ports, opposite sides of said valve body provided with separated piping ports, said valve body provided with a water supply port between 30 said piping ports, an outwardly opening check valve in one of said first-named valve ports, said valve plug provided with passages separated by a separating wall in said plug, each of said passages having a passage port, said valve plug provided with an additional port in one of said 35 passages in substantially continuous communication with the other of said first-named valve ports, one of said passage ports normally closed by a wall of said valve body and arranged to be placed in communication with either of said piping ports by rotation of said valve plug in opposite directions through an angle of substantially ninety degrees, the other of said passage ports normally registerable with said water supply port and arranged to span said water supply port and either of said piping ports by rotation of said valve plug in opposite directions through an angle of substantially forty-five degrees, hoses extending from said piping ports, and releasable means for selectively connecting said 40 hoses to said respective faucets.

said water supply port and arranged to span said water supply port and either of said piping ports by rotation of said valve plug in opposite directions, hoses extending from said piping ports, and releasable connecting means for said respective hoses to connect said hoses to said piping. 5

5. In means for cleaning the pipes including the coils of a dispensing system having a plurality of faucets, the respective faucets having communication with said respective coils and the respective pipes having normal communication with containers for beverage, of means whereby to disconnect said pipes from dispensing connection with said containers, a coupling between said pipes for connecting communication between the same, a pump comprising a casing and a reciprocating member, said casing having a pump port at each end of said reciprocating member, a valve between said pump ports comprising a body having valve ports communicating with said respective pump ports and a valve plug between said valve ports, opposite sides of said valve body provided with separated piping ports, said valve body provided with a water supply port between said piping ports, an outwardly opening check 25 valve in one of said first-named valve ports, said valve plug provided with passages separated by a separating wall in said plug, each of said passages having a passage port, said valve plug provided with an additional port in one of said 30 passages in substantially continuous communication with the other of said first-named valve ports, one of said passage ports normally closed by a wall of said valve body and arranged to be placed in communication with either of said piping 35 ports by movement of said valve plug in opposite directions through an angle of substantially ninety degrees, the other of said passage ports normally registerable with said water supply port and arranged to span said water supply port and either of said piping ports by rotation of said valve plug in opposite directions through an angle of substantially forty-five degrees, hoses extending from said piping ports, and releasable means for selectively connecting said 40 hoses to said respective faucets. 45

SABATINO PETRICONE.
